UNITED STATES PATENT OFFICE

170,695

COMBINED GARBAGE AND TRASH CAN HOLDER

Stanley W. Kane, Racine, Wis.

Application January 26, 1953, Serial No. 23,289

Term of patent 14 years

(Cl. D58—17)

To all whom it may concern:

Be it known that I, Stanley W. Kane, a citizen of the United States, residing at Racine, State of Wisconsin, have invented a new, original, and ornamental Design for a Combined Garbage and Trash Can Holder, of which the following is a specification, reference being had to the accompanying drawing, forming a part hereof.

The figure is a perspective view of a combined garbage and trash can holder showing my new design.

The attached chains are shown broken to indicate indefinite length.

I claim:

The ornamental design for a combined garbage and trash can holder, as shown and described.

STANLEY W. KANE.
